UNITED STATES PATENT OFFICE.

AURELIUS M. McSPADDEN, OF ST. LOUIS, MISSOURI.

GREASE PUMP.

Application filed January 11, 1922. Serial No. 528,515.

To all whom it may concern:

Be it known that I, AURELIUS M. Mc-
SPADDEN, a citizen of the United States,
residing in the city of St. Louis and State
5 of Missouri, have invented new and useful
Improvements in Grease Pumps, of which
the following is a specification.

This invention relates to grease machines
or pumps and particularly to a type of
10 pump which is adapted to be used with a
grease container in the form of a cylinder
which operates as a part of the pump when
set up to co-operate with the pump plunger.
Pumps of this type are very useful around
15 garages or similar establishments for forc-
ing grease into crank cases or grease cups.

The general object of the invention is to
provide a grease pump having a cylinder
which is the container in which the grease is
20 delivered to the garage, or other establish-
ment using the pump, and to provide a co-
operating construction for the pump and
container which will enable the container to
25 be readily handled without injury; and
which will facilitate the placing and secur-
ing of the container in position to co-operate
with the plunger of the pump; also to pro-
vide an improved roller mounting for the
30 base-plate of the pump which will facilitate
its being moved from place to place in the
garage, but so constructed as to overcome
any tendency of the rollers to permit the
pump to slide or skid when it is being op-
35 erated; another object of the invention is to
construct the container or pump cylinder so
that it can stand upright on the floor if
desired.

Further objects of the invention will ap-
pear hereinafter.

40 The invention consists in the novel fea-
tures, and in the general combination of
parts to be particularly described herein-
after, all of which contribute to produce a
simple and efficient grease pump. A pre-
45 ferred embodiment of my invention will be
particularly described in the following speci-
fication, while the broad scope of my inven-
tion will be pointed out in the appended
claims.

50 In the drawing,

Figure 1 is a side elevation and partial
section through the pump embodying my
invention;

Figure 2 is a plan of the pump shown in
Figure 1;

Figure 3 is a vertical section upon an en-
larged scale through the pump, taken about
on the line 3-3 of Figure 2; and

Figure 4 is a vertical section taken through
the bottom of the pump cylinder or grease
60 container and showing the same with its
closure secured in place.

The pump includes a base-plate 1 which
may have four arms 2 projecting outwardly
from the central portion of the base-plate,
65 at which point an elevated seat 3 is pro-
vided to receive the lower end of a cylin-
drical container 4. This seat has a cylin-
drical side face 5. The container 4 consists
of a cylindrical shell 6, the lower end of 70
which projects downwardly and extends over
the cylindrical face 5, and the cylinder is
provided with a countersunk head 7 which
is adapted to rest flat upon the seat 3 (see
Figures 1 and 3). The head is provided 75
with an outlet nipple 8 which is preferably
located centrally on the head, and the body
of this nipple is substantially conical so as
to be received upon a conical counterbore
9 which is formed at the center of the seat 80
3. The lower end of the nipple terminates
in a threaded neck 10 for a purpose which
will appear hereinafter. The base-plate
supports a frame 11 which may include two
or more standards 12 which are simply 85
stems or rods, the lower ends of which are
secured to the base-plate in such a way that
these bars 12 are parallel to the axis of the
cylinder or container 4 when it has been
applied to the seat. The frame includes an 90
upper frame 13 which is mounted on the
upper ends of the standards 12 and operates
as a guide for a stem or rod 14 which ex-
tends up from a pump plunger or piston 15
which is adapted to fit the bore of the con- 95
tainer, as a piston fits its cylinder.

Any suitable means may be provided for
forcing the plunger down into the container.
For this purpose the stem 14 may be
threaded so as to co-operate with the nut 100
16 through which it passes, the nut being
rigid with a bevel gear 17 which may be
rotated by a pinion 18 carried by a shaft
19 to which a crank 20 is attached so as to
rotate in a vertical plane.

I provide means guided on the frame for

engaging and holding the upper end of the container when it is co-operating with the plunger 15. This means is preferably in the form of a cross-head 21 which is guided 5 to slide on the standards 12 toward or from the seat 3, and this cross-head may be provided with a set screw 22 for securing it in position. Its central portion is provided 10 with a conical-bore 23 and a counter-bore 24 to fit the upper end of the cylindrical shell 6.

When the gear wheel 17 and nut 16 are being rotated, the stem 14 is prevented from 15 rotating by means of a fixed feather or tongue 25 which runs in a longitudinal groove or slot 26 extending along the stem, and in order to enable the amount of grease ejected from the pump to be measured, I provide the stem 14 with a collar 27 which 20 may be adjustably clamped at any point by means of a set screw 28 fitting in the groove 26. This collar 27 carries a scale 29 which extends longitudinally with the stem and is graduated so as to indicate units of measure, 25 for example, pints or pounds. This scale may be guided through openings 30 formed in the upper frame 13 and cooperates with a small pointer 31 mounted on the frame at a convenient point (see Fig. 1).

30 The counter-bore 9 is formed on a duct 32 which passes downwardly through the seat and extends laterally therein, terminating at the side in a delivery nipple 33 to which a flexible hose 34 may be attached.

35 By reason of the fact that the head 7 at the bottom of the container is countersunk, the container can rest upon the floor 35 in an upright position (see Fig. 4), that is to say, the cylindrical shell 6 extends down beyond the head 7 a sufficient distance to hold 40 the nipple clear of the floor, even while the nipple is carrying a cap 36 which screws upon the threads 10 referred to above. It should be understood that these containers 45 are furnished to the garage, full of grease with the cap or closure 36 in place and with a removable cover, not illustrated, on the upper end of the shell 6. When it is desired to use the grease it is simply necessary to 50 remove the cover of the can or container and also the screw cap 36 and then set the container in position, as illustrated in Figure 1.

55 The seat 3 extends up sufficiently to prevent any possibility of the weight of the container coming upon the lower edge of the shell. In other words, the principal part of the weight exerts itself as pressure developed between the conical nipple 8 and the conical seat 9. Hence, when pressure is 60 developed in the grease within the container, this pressure between the nipple and the counter-bore 9 will tend to prevent any grease from finding exit at the base of the can. Of course, such an escape of the grease

would be resisted by the seat 3 and the head 7 to a certain extent even if the conical nipple were not employed.

However, I prefer to use the conical nipple because it assists in guiding the container to its central position when the same is being placed on the base plate. After the container is set up, the cross-head 21 is then moved down into engagement with it and secured in place by means of the set 75 screw 22. The plunger is then advanced until it forces the grease to the outlet end of the hose; the scale 29 should then be adjusted so that it indicates zero and the crank 20 should be turned again so as to 80 deliver as much grease as the purchaser desires.

I provide improved means for mounting the pump on rollers which will facilitate its being moved from place to place around a garage, but the rollers are mounted in such a way that they will not increase the mobility of the pump when the crank 20 is being rotated. For this purpose I prefer to let the base-plate rest directly upon the floor 85 at one side of the container, for which purpose I may provide it with short feet or legs 37. On the other side I provide the base-plate with a pair of rollers 38 and these rollers are mounted so that they rotate in a plane transverse to the plane in which the crank 20 swings. Hence, when the crank is rotated they do not tend to rotate, and hence they give substantially the same effect as though they were constructed like the feet 90 37, because any tendency of the crank to move the pump is exerted in a plane at right angles to the plane of rotation of the wheel or roller.

100 While it is not necessary for the plane of rotation of these rollers to be exactly at right angles to the plane of rotation of the crank, nevertheless, I prefer to mount them so that they are in a plane substantially at right angles to the plane in which the crank 105 swings.

At a convenient point the base-plate is provided with a foot plate 39 (see Figure 2) upon which the operator of the pump may exert pressure with his foot in order to hold 110 the base-plate securely in position when the crank is being rotated.

What I claim is:

1. In a grease pump, the combination of 115 a base-plate, a cylinder supported thereon, a hose connected with the lower end of the cylinder, a frame, a plunger guided in the frame, means for forcing the plunger down into the cylinder, including a crank mounted to swing in a substantially vertical plane, and rollers carried by the base-plate for supporting the same on the floor, and mounted to rotate in a plane transverse to the plane of rotation of the crank.

120 2. In a grease pump, the combination of

a base-plate, a cylinder supported thereon, a hose connected with the lower end of the cylinder, a frame, a plunger guided in the frame, means for forcing the plunger down into the cylinder, including a crank mounted to swing in a substantially vertical plane, said base-plate constructed to rest upon the floor at one side of the container and having a pair of rollers at the opposite side of the container for supporting the base-plate on the floor, said rollers being mounted to rotate in a plane substantially at right angles to the plane of rotation of the crank. In testimony whereof, I have hereunto set my hand.

AURELIUS M. McSPADDEN.
